(57) **ABSTRACT**

A supply system, in which each of a plurality of printers holds ink specification information for specifying a kind of ink to be supplied to the printer, includes an ink supply apparatus. The ink supply apparatus includes a plurality of ink storage units storing different kinds of ink, a plurality of ink discharging units each of which is coupled to a corresponding one of the ink storage units and discharges, to the printer, the ink stored in the coupled ink storage unit, an information reading unit that reads the ink specification information held by the printer, and a control unit that controls an ink discharging unit of the ink discharging units and causes the ink discharging unit to discharge ink, the ink discharging unit being coupled to the ink storage unit storing the kind of ink specified by the ink specification information read by the information reading unit.

SUPPLY SYSTEM

The present application is based on, and claims priority from JP Application Serial Number 2022-112219, filed Jul. 13, 2022, the disclosure of which is hereby incorporated by reference herein in its entirety.

BACKGROUND

1. Technical Field

The present disclosure relates to a supply system for supplying ink to printers.

2. Related Art

There have been technologies for refilling recording agent containers of printers with recording agents. In the technology of JP-A-2001-301198, a recording agent container is detached from a printer and is set on an ink refill station by a user. When the ink refill station determines that the recording agent container set on the ink refill station is not reusable, the recording agent container is collected at the ink refill station. On the other hand, when the ink refill station determines that the recording agent container set on the ink refill station is reusable, the ink refill station refills the recording agent container with a recording agent that is suitable for the recording agent container among a plurality of recording agents stored in recording agent storage units.

The recording agent container supposed in the technology of JP-A-2001-301198 is handled by a user (i) when the recording agent container is detached from the printer, (ii) when the recording agent container is attached to an ink refill station, and (iii) during a period after the recording agent container is detached from the printer before it is attached to an ink refill station. Therefore, the recording agent container may be inappropriately handled by the user or may be accidentally dropped by the user from a height. For this reason, the recording agent container supposed in the technology of JP-A-2001-301198 has a high risk of damage. Further, the life of the recording agent container supposed in the technology of JP-A-2001-301198 is set to be shorter than that of the printer body.

Damaged recording agent containers and recording agent containers whose lives have expired are determined not to be reusable and are collected at the ink refill station. The collected recording agent containers are discarded or become objects of material recycling. In the field of refilling the recording agent, a technology capable of reducing the burden on the environment is desired.

SUMMARY

According to an aspect of the present disclosure, a supply system for supplying ink to a plurality of printers is provided. The supply system, in which each of the plurality of printers holds ink specification information for specifying a kind of ink to be supplied to the printer, includes an ink supply apparatus. The ink supply apparatus includes a plurality of ink storage units storing different kinds of ink, a plurality of ink discharging units each of which is coupled to a corresponding one of the plurality of ink storage units and discharges, to the printer, the ink stored in the coupled ink storage unit, an information reading unit that reads the ink specification information held by the printer, and a control unit that controls an ink discharging unit of the plurality of ink discharging units and causes the ink dis-

charging unit to discharge ink, the ink discharging unit being coupled to the ink storage unit storing the kind of ink specified by the ink specification information read by the information reading unit.

BRIEF DESCRIPTION OF THE DRAWINGS

FIG. 1 is an explanatory view illustrating the overall configuration of a supply system of a first embodiment.

FIG. 2 is an explanatory view illustrating the shapes of end portions of discharge coupling units of an ink supply apparatus and the shapes of end portions of reception coupling units of a printer.

FIG. 3 is an explanatory view illustrating the configuration of a discharge coupling unit.

FIG. 4 is an explanatory view illustrating the overall configuration of a supply system of a second embodiment.

FIG. 5 is an explanatory view illustrating the shapes of the leading end portions of discharge coupling units of an ink supply apparatus and the shapes of the leading end portions of reception coupling units of a printer.

DESCRIPTION OF EXEMPLARY EMBODIMENTS

A. First Embodiment

A1. Configuration of Supply System

FIG. 1 is an explanatory view illustrating the overall configuration of a supply system **1000** of a first embodiment. The supply system **1000** supplies ink to a plurality of printers. In FIG. 1, as the plurality of printers, three printers **100A**, **100B**, and **100C** are shown. In this specification, when the printers are referred to without distinguishing the three printers **100A**, **100B**, and **100C**, they are referred to as the “printer **100**” or the “printers **100**”.

The supply system **1000** includes an ink supply apparatus **200** and a management server **300**. The management server **300** is connected to the ink supply apparatus **200** and the printers **100A**, **100B**, and **100C** so as to be capable of communicating with them.

Each of the printers **100A**, **100B**, and **100C** is a printer which receives supplied ink and performs printing (see the middle right part and bottom part of FIG. 1). The printers **100A**, **100B**, and **100C** are installed in different departments in a company. The printers **100A** to **100C** are installed on bases **400A** to **400C**. Each of the bases **400A** to **400C** has wheels **410**. The bases **400A** to **400C** can be moved by applying an external force to rotate the wheels **410**.

This configuration makes it possible for each of the printers **100A** to **100C** installed on the bases **400A** to **400C** to be moved to the installation location of the ink supply apparatus **200** (see arrows **A1** of FIG. 1). In the present embodiment, the printers **100** are moved from the individual departments in the company to the installation location of the ink supply apparatus **200** in the general affairs department. As a result, ink can be supplied from the ink supply apparatus **200** to each of the printers **100A** to **100C** installed in the different places.

Each of the printers **100A** to **100C** holds ink specification information **Ii** for identifying the kind of ink to be supplied to the corresponding printer **100A**, **100B**, or **100C**. More specifically, the printers **100A** to **100C** have a two-dimensional barcode **160** representing the ink specification information **Ii**, on the outside of the printers **100A** to **100C**. The ink specification information **Ii** regarding each of the printers **100A** to **100C** includes information on the model of the

printer, information for identifying the individual printer, and information indicating the ink set which the printer is using. Hereinafter, when the configurations of the printers **100A** to **100C** are described, the description will be made taking the printer **100A** as an example.

The printer **100A** includes m (m is an integer of 1 or greater) ink storage units **111** to **11m**, m reception coupling units **121R** to **12mR**, m ink sensors **131** to **13m**, a control unit **140**, an output unit **150**, and a two-dimensional barcode **160**.

The ink storage units **111** to **11m** store ink to be used when printing is performed by the printer **100A**. The ink storage units **111** to **11m** store ink of different colors.

The reception coupling units **121R** to **12mR** are coupled to the ink storage units **111** to **11m**, respectively. Each of the reception coupling units **121R** to **12mR** is coupled to one of the plurality of ink discharging units **221** to **22n** included in the ink supply apparatus **200**, thereby receiving ink. The ink received from the ink discharging units **22i** (i is an integer from 1 to m) by the reception coupling units **121R** to **12mR** is stored in the corresponding ink storage units **111** to **11m**.

The ink sensors **131** to **13m** can respectively detect that the amounts of ink stored in the ink storage units **111** to **11m** of the printer **100A** are smaller than a predetermined threshold.

The output unit **150** controlled by the control unit **140** displays a variety of information including characters, images, and sounds. Specifically, the output unit **150** is a liquid crystal panel equipped with a speaker.

The control unit **140** includes a CPU **141** which is a processor, a RAM **142**, and a ROM **143** (see the middle right part of FIG. 1). The RAM **142** includes a main storage device and an auxiliary storage device. The CPU **141** realizes various functions by loading computer programs stored in the ROM **143** or the auxiliary storage device to the main storage device and executing them.

The two-dimensional barcode **160** indicates the ink specification information I_i . As described above, each ink specification information I_i indicates the kind of ink to be supplied to a corresponding one of the printers **100A** to **100C**.

The printers **100B** and **100C** are different models of printers from the printer **100A**. However, the functions of the individual portions of the printers **100B** and **100C** are the same as the functions of the individual portions of the printer **100A**. The printers **100A**, **100B**, and **100C** are different in the ink sets which are used by those printers.

The ink supply apparatus **200** is an apparatus for supplying ink to the printers **100** (see the middle left part of FIG. 1). The ink supply apparatus **200** stores all kinds of ink which can be used in the printers **100A** to **100C**. The ink supply apparatus **200** is installed in a general affairs department in a company. The ink supply apparatus **200** includes n (n is an integer equal to or greater than 2 and equal to or greater than m) ink storage units **211** to **21n**, n ink discharging units **221** to **22n**, an information reading unit **230**, a control unit **240**, and an output unit **250**.

The n ink storage units **211** to **21n** each store different kinds of ink. The n ink discharging units **221** to **22n** are coupled to the n ink storage units **211** to **21n** (also referred to as the ink storage units **21i**), respectively, and discharge ink, stored in the ink storage units **21i** coupled thereto, to the printers **100A** to **100C**. The number of ink storage units **211** to **21n** included in the ink supply apparatus **200** is the same as the number of ink discharging units **221** to **22n** included in the ink supply apparatus **200**.

Each of the n ink discharging units **221** to **22n** includes a discharge coupling unit **22iF** (i is an integer from 1 to n), and a coupling tube **22iT** (i is an integer from 1 to n). The discharge coupling unit **22iF** is coupled to one of the n reception coupling units **12jR** (j is an integer from 1 to m) of the printers **100A** to **100C**, and discharges ink. The coupling tube **22iT** couples the discharge coupling unit **22iF** to the ink storage unit **21i**. The coupling tube **22iT** is a flexible tube.

FIG. 2 is an explanatory view illustrating the shapes of end portions of the discharge coupling units **22iF** (i is an integer from 1 to n) of the ink supply apparatus **200** as seen from the front, and the shapes of end portions of the reception coupling units **12jR** (j is an integer from 1 to m) of a printer **100** as seen from the front. In the printer **100A** and the ink supply apparatus **200**, a reception coupling unit **12jR** and a discharge coupling unit **22iF** for passing different kinds of ink are configured in such shapes that they cannot be coupled to each other. A reception coupling unit **12jR** and a discharge coupling unit **22iF** for passing the same kind of ink are configured in shapes such that they can be coupled to each other.

The reception coupling unit **121R** of the printer **100A** and the discharge coupling unit **221F** of the ink supply apparatus **200** pass the same kind of ink (see the upper part of FIG. 2). The shape of the end portion of the reception coupling unit **121R** of the printer **100A** is a circle. The shape of the end portion of the discharge coupling unit **221F** of the ink supply apparatus **200** is a circle having such a size that the end portion of the discharge coupling unit **221F** can be inserted into the reception coupling unit **121R** of the printer **100A**.

The reception coupling unit **122R** of the printer **100A** and the discharge coupling unit **222F** of the ink supply apparatus **200** pass the same kind of ink (see the middle part of FIG. 2). The shape of the end portion of the reception coupling unit **122R** of the printer **100A** is an equilateral triangle. The shape of the end portion of the discharge coupling unit **222F** of the ink supply apparatus **200** is an equilateral triangle having such a size that the end portion of the discharge coupling unit **222F** can be inserted into the reception coupling unit **122R** of the printer **100A**.

The reception coupling unit **123R** of the printer **100A** and the discharge coupling unit **223F** of the ink supply apparatus **200** pass the same kind of ink (see the lower part of FIG. 2). The shape of the end portion of the reception coupling unit **123R** of the printer **100A** is a regular pentagon. The shape of the end portion of the discharge coupling unit **223F** of the ink supply apparatus **200** is a regular pentagon having such a size that the end portion of the discharge coupling unit **223F** can be inserted into the reception coupling unit **123R** of the printer **100A**.

Each discharge coupling unit **22iF** has an end portion the shape of which cannot be inserted into a reception coupling unit **12jR** for passing a different kind of ink from the kind of ink for the discharge coupling unit **22iF**.

This configuration enables appropriate kinds of ink to be supplied from the ink supply apparatus **200** to the printers **100** by coupling the discharge coupling units **22iF** of the ink supply apparatus **200** to the reception coupling units **12jR** of the printers **100**. Further, it is possible to prevent inappropriate kinds of ink from being supplied from the ink supply apparatus **200** to the printers **100**.

The information reading unit **230** can read the ink specification information I_i held by the individual printers **100A** to **100C**. Specifically, the information reading unit **230** is a

barcode reader capable of optically reading the two-dimensional barcode 160 indicating the ink specification information II.

The output unit 250 controlled by the control unit 240 outputs a variety of information including characters, images, and sounds. Specifically, the output unit 250 is a liquid crystal panel equipped with a speaker.

The control unit 240 includes a CPU 241 which is a processor, a RAM 242, and a ROM 243. The RAM 242 includes a main storage device and an auxiliary storage device (see the middle left part of FIG. 1). The CPU 241 realizes the following functions by loading computer programs stored in the ROM 243 or the auxiliary storage device to the main storage device and executing them.

The control unit 240 controls the ink discharging unit 22i, of the n ink discharging units 221 to 22n, coupled to the ink storage unit 21i storing the kind of ink corresponding to ink specification information II read by the information reading unit 230, such that the ink discharging unit 22i discharges ink. The control unit 240 performs a display corresponding to the ink specification information II read by the information reading unit 230, on the output unit 250.

Since the printers 100 and the ink supply apparatus 200 are configured as described above, appropriate kinds of ink can be supplied from the ink supply apparatus 200 to the printers 100A to 100C by using the ink specification information II held by the printers 100A to 100C. Further, appropriate kinds of ink can be supplied to the printers 100A to 100C without detaching, from the printers 100A to 100C, the ink storage units 111 to 11m for storing ink in the printers 100A to 100C. For this reason, the printers 100A to 100C can be consistently used in their entirety without discarding the ink storage units 111 to 11m for storing ink in the printers 100A to 100C or using them as objects of material recycling within shorter periods as compared to the bodies of the printers 100A to 100C. Therefore, the burden on the environment is reduced.

FIG. 3 is an explanatory view illustrating the configuration of a discharge coupling unit 22iF (i is an integer from 1 to n) (see also the top of the left part of FIG. 1). The discharge coupling unit 22iF includes a holding portion 22iH, a nozzle portion 22iN, and an ink sensing unit 22iS.

The holding portion 22iH is a portion held by the user with a hand when ink is discharged from the ink supply apparatus 200 to the printers 100A to 100C through the discharge coupling unit 22iF. The holding portion 22iH is not inserted into the printers 100A to 100C. The nozzle portion 22iN is inserted into a reception coupling unit 12jR of the printer 100A, 100B, or 100C such that ink can be discharged from the ink supply apparatus 200 to the printer 100A, 100B, or 100C through the discharge coupling unit 22iF, and discharges ink (see the top right part of FIG. 1).

The ink sensing unit 22iS is provided on the nozzle portion 22iN of the discharge coupling unit 22iF. The ink sensing unit 22iS is inserted into a reception coupling unit 12jR (j is an integer from 1 to m) of the printer 100A, 100B, or 100C when ink is discharged from the ink supply apparatus 200 to the printer 100A, 100B, or 100C through the discharge coupling unit 22iF (see the top right part of FIG. 1). The ink sensing unit 22iS can detect ink.

The ink sensing unit 22iS includes a switch that can turn on/off an electric circuit, and a float that is coupled to the switch and floats on ink. The individual ink discharging units 221 to 22n of the ink supply apparatus 200 stop discharging ink when the ink sensing units 221S to 22nS detect ink, respectively. More specifically, as the level of ink in the reception coupling unit 12jR rises, the float of the ink

sensing unit 22iS is moved, and the electric circuit is turned off, whereby the ink discharging unit 22i stops discharging ink.

This configuration enables ink to be supplied to the printers 100A to 100C without making ink spill out of the reception coupling units 12jR of the printers 100A to 100C.

The management server 300 includes a CPU 341 which is a processor, a RAM 342, and a ROM 343 (see the middle part of FIG. 1). The RAM 342 includes a main storage device and an auxiliary storage device. The CPU 341 realizes the following functions by loading computer programs stored in the ROM 343 or the auxiliary storage device to the main storage device and executing them.

The management server 300 holds, in the auxiliary storage device, information on the kinds of ink to be used by the respective printers 100A, 100B, and 100C in association with information specifying the printers 100A, 100B, and 100C.

A2. Operation of Supply System:

20 Each of the printers 100A to 100C transmits an ink supply request Rs to the management server 300 when the amount of ink stored in the corresponding printer 100A, 100B, or 100C is smaller than a predetermined threshold. An ink supply request Rs is a signal indicating that it is required to supply ink to the printer 100 which is the transmitter of the ink supply request Rs. More specifically, when an ink sensor 13j of the ink sensors 131 to 13m detects that the amount of ink stored in the ink storage unit 11j is smaller than the predetermined threshold, the control unit 140 of the printer 100 transmits an ink supply request Rs to the management server 300 (see the top right part and middle right part of FIG. 1).

25 Further, the control unit 140 displays, on the output unit 150, information indicating that the amount of ink stored in the ink storage unit 11j is smaller than the predetermined threshold, and a message for urging the ink storage unit 11j to receive supply of the ink same as the ink stored in the ink storage unit 11j from the ink supply apparatus 200. When the user of the printer 100 sees the display on the output unit 40 150, the user moves the printer 100 to the place where the ink supply apparatus 200 is installed (see the arrows A1 of FIG. 1).

30 When the ink supply request Rs is received, the management server 300 transmits, to the ink supply apparatus 200, a supply instruction Is including information indicating the printer 100 having transmitted the ink supply request Rs (see the middle part of FIG. 1). The supply instruction Is is a signal indicating that it is required to supply ink to the printer 100 having transmitted the ink supply request Rs.

35 When the supply instruction Is is received, the ink supply apparatus 200 outputs, to the output unit 250, information for urging supply of ink to the printer 100 having transmitted the ink supply request Rs. More specifically, when the supply instruction Is is received, the control unit 240 of the ink supply apparatus 200 controls the output unit 250 to display information on the printer 100 having transmitted the ink supply request Rs and a message for urging supply of ink to the printer 100. This display makes it possible for the operator of the ink supply apparatus 200 to recognize the printer 100 requiring supply of ink from the ink supply apparatus 200.

40 When the printer 100 arrives, the operator of the ink supply apparatus 200 reads the two-dimensional barcode 160 attached to the printer 100, with the information reading unit 230. The control unit 240 of the ink supply apparatus 200 activates one or more ink discharging units 22i coupled to one or more ink storage units 21i storing ink indicated by

the ink specification information I_i . The operator of the ink supply apparatus 200 supplies ink to the ink storage units $11j$ of the printer 100 , using the one or more activated ink discharging units $22i$. At that time, the nozzle portion $22iN$ of the discharge coupling unit $22iF$ is inserted into the reception coupling unit $12jR$, having a corresponding shape, of the printer 100 (see FIG. 2).

By performing this process, the operator of the ink supply apparatus 200 supplies ink from the ink supply apparatus 200 to the printer 100 in response to the output of the output unit 250 originated from the supply instruction I_s , whereby it is possible to refill the printer 100 with ink before the printer 100 is caused to be unable to print due to a shortage of ink. Further, when the printer 100 stores a sufficient amount of ink, it is possible to avoid refilling the printer 100 with ink. In other words, it is possible to reduce the number of times of refilling the printer 100 with ink.

The ink supply request R_s of the present embodiment is also referred to as a “first signal”. The supply instruction I_s is also referred to as a “second signal”.

B. Second Embodiment

In the first embodiment, the printers $100A$ to $100C$ are moved to the installation location of the ink supply apparatus 200 to receive ink from the ink supply apparatus 200 (see the arrows $At1$ of FIG. 1). However, in a second embodiment, an ink supply apparatus $200b$ is moved to the installation locations of the printers $100A$ to $100C$ to supply ink to the printers $100A$ to $100C$. Accordingly, in the second embodiment, the printers $100A$ to $100C$ are not installed on the movable bases $400A$ to $400C$. Further, the ink supply apparatus $200b$ of the second embodiment includes a fixing tool 280 which is not included in the ink supply apparatus 200 of the first embodiment. Other points of a supply system $1000b$ of the second embodiment are the same as those of the supply system 1000 of the first embodiment.

FIG. 4 is an explanatory view illustrating the overall configuration of the supply system $1000b$ of the second embodiment. The ink supply apparatus $200b$ includes the fixing tool 280 for fixing the ink supply apparatus $200b$ to a human body. More specifically, the fixing tool 280 is a pair of belts for holding both shoulders of an operator OP. The operator OP of the ink supply apparatus $200b$ can lift the ink supply apparatus $200b$ onto their back, using the fixing tool 280 . The ink supply apparatus $200b$ is made to have such a weight that it can be lifted onto the back of the operator OP.

Similarly to the supply system 1000 of the first embodiment, when a supply instruction I_s is received, the control unit 240 of the ink supply apparatus $200b$ displays, on the output unit 250 , information on the printer 100 having transmitted the ink supply request R_s and a message for urging supply of ink to the printer 100 . This display makes it possible for the operator of the ink supply apparatus $200b$ to recognize the printer 100 requiring supply of ink from the ink supply apparatus $200b$. The operator of the ink supply apparatus $200b$ lifts the ink supply apparatus $200b$ onto their back, and moves to the installation location of the printer 100 requiring ink supply (see an arrow $At2$ of FIG. 4).

When the operator OP of the ink supply apparatus $200b$ arrives at the installation location of the printer 100 , the two-dimensional barcode 160 attached to the printer 100 is read with the information reading unit 230 . The control unit 240 of the ink supply apparatus $200b$ activates one or more ink discharging units $22i$ coupled to one or more ink storage units $21i$ storing ink indicated by the ink specification information I_i . The operator OP of the ink supply apparatus

$200b$ supplies ink to the ink storage units $11j$ of the printer 100 , using the activated ink discharging units $22i$.

This configuration makes it possible for the operator OP with the ink supply apparatus $200b$ fixed on the operator OP to move to the installation location of the printer 100 and supply ink from the ink supply apparatus $200b$ to the printer 100 .

C. Third Embodiment

In the first embodiment, in the ink supply apparatus 200 , the discharge coupling units $22iF$ (i is an integer from 1 to n) for passing different kinds of ink have sectional shapes different from one another (see FIG. 2). In the printer 100 , the reception coupling units $12jR$ (j is an integer from 1 to m) for passing different kinds of ink have sectional shapes different from one another. Further, a reception coupling unit $12jR$ and a discharge coupling unit $22iF$ for passing the same kind of ink have sectional shapes that are the same but are different in size. In a third embodiment, reception coupling units $12jR$ and discharge coupling units $22iF$ have shapes different from those of the first embodiment. Other points of a supply system of the third embodiment are the same as those of the supply system 1000 of the first embodiment.

FIG. 5 is an explanatory view illustrating the shapes of the leading end portions of the discharge coupling units $22iF$ (i is an integer from 1 to n) of the ink supply apparatus 200 and the shapes of the leading end portions of the reception coupling units $12jR$ (j is an integer from 1 to m) of the printer 100 . The discharge coupling units $22iF$ of the ink supply apparatus 200 and the reception coupling units $12jR$ have fixing tools $22iP$ (i is an integer from 1 to n) and fixing tools $12jQ$ (j is an integer from 1 to m) to be mutually fitted, respectively. A discharge coupling unit $22iF$ and a reception coupling unit $12jR$ corresponding to each other are fixed to each other by fixing tool $22iP$ and fixing tool $12jQ$.

The leading end portion of each discharge coupling unit $22iF$ (i is an integer from 1 to n) of the ink supply apparatus 200 has a square flow port $22i0$ at the center. Further, the leading end portion has eight square regions arranged so as to surround the flow port $22i0$. The square flow port $22i0$ and the eight square regions arranged so as to surround the flow port $22i0$ have a square outline as a whole. Of the eight square regions, some regions RP protrude as compared to the other regions in the ink flow direction. In the discharge coupling units $22iF$ illustrated in FIG. 5, the regions RP protruding as compared to the other regions are shown by hatching.

The leading end portion of each reception coupling unit $12jR$ (j is an integer from 1 to m) of the printer 100 has a square flow port $12j0$ at the center. Further, the leading end portion has eight square regions arranged so as to surround the flow port $12j0$. The square flow port $12j0$ and the eight square regions arranged so as to surround the flow port $12j0$ have a square outline as a whole. Of the eight square regions, some regions RR are recessed in the ink flow direction as compared to the other regions. In the reception coupling units $12jR$ illustrated in FIG. 5, the regions RR recessed as compared to the other regions are shown by hatching.

In a reception coupling unit $12jR$ and a discharge coupling unit $22iF$ for passing the same kind of ink, the recessed region RR of the reception coupling unit $12jR$ and the protruding region RP of the discharge coupling unit $22iF$ are at positions corresponding to each other. In other words, the recessed region RR of the reception coupling unit $12jR$ is configured to receive the protruding region RP of the corresponding discharge coupling unit $22iF$.

With this configuration, also, a reception coupling unit 12j/R and a discharge coupling unit 22i/F for passing different kinds of ink cannot be coupled to each other. Further, a reception coupling unit 12j/R and a discharge coupling unit 22i/F for passing the same kind of ink can be coupled to each other.

This configuration also makes it possible to supply appropriate kinds of ink from the ink supply apparatus 200 to the printers 100 by connecting the discharge coupling units 22i/F of the ink supply apparatus 200 to the reception coupling units 12j/R of the printers 100. Further, it is possible to prevent inappropriate kinds of ink from being supplied from the ink supply apparatus 200 to the printers 100.

D. Other Embodiments

D1. First of Other Embodiments

(1) In the above-described embodiments, the ink sensing unit 22i/S capable of detecting ink includes the float which floats on ink (see the top right part of FIG. 1). However, the ink sensing unit 22i/S for detecting the amount of ink in the reception coupling unit 12j/R may be one for detecting the amount of ink according to other principles. For example, the ink sensing unit may be one for detecting that the amount of ink is smaller than a threshold, in response to a change in the amount of current flowing through the ink or a change in the amount of light reflected.

(2) In the above-described embodiments, when an ink sensor 13j detects that the amount of ink stored in the ink storage unit 11j is smaller than the predetermined threshold, the control unit 140 of the printer 100 transmits an ink supply request Rs to the management server 300 (see the top right part and middle right part of FIG. 1). It is also possible to set, as the predetermined threshold, such an amount of residual ink with which the printer can print a predetermined amount. Also, it is possible to set, as the predetermined threshold, a value indicating that ink has substantially run out.

(3) In the above-described embodiments, when the amount of ink stored in each printer 100A, 100B, or 100C is smaller than the predetermined threshold, an ink supply request Rs is transmitted to the management server 300 (see the right part and bottom part of FIG. 1). However, a plurality of thresholds for the amount of ink of the printers 100 may be set such that whenever the amount of ink reaches one of the thresholds, a signal for notification is transmitted to the management server 300. Also, whenever a predetermined period of time elapses, or whenever a predetermined process such as printing one page is performed, each of the printers 100 may transmit the residual amount of ink detected by each sensor to the management server 300 such that the management server 300 can manage the residual amount of ink of each printer 100.

(4) In the above-described embodiments, each of the printers 100A to 100C has the two-dimensional barcode 160 indicating the ink specification information l_i (see the middle right part of FIG. 1). However, each printer may hold the ink specification information l_i in other forms such as a one-dimensional barcode, an RFID (Radio Frequency Identification) tag, or a magnetic medium. The information reading unit 230 provided in the ink supply apparatus 200 may be configured to be able to read information stored in such media.

(5) In the above-described embodiments, the ink specification information l_i of each printer 100 includes information on the model, information for identifying the printer,

and information indicating the ink set used by the printer (see the middle right part of FIG. 1). However, the ink specification information l_i may include, for example, information for identifying the printer 100 without including information indicating the ink set used by the printer. In such an aspect, for example, the management server 300 can hold, in a storage device, correspondence information in which printers are associated with the ink sets used in the printers. When the management server 300 receives an ink supply request Rs from a printer, the management server 300 transmits, with reference to the correspondence information, a supply instruction l_s including information on the ink set used in the printer having transmitted the ink supply request Rs, to the ink supply apparatus.

(6) Also, when the models of the printers are in one-to-one correspondence with the ink sets used in the printers, the ink specification information l_i may include information for identifying the models of the printers 100 without including information indicating the ink sets used. The information for identifying the models of the printers 100 can be handled in the same way as the information of the above-mentioned aspect for identifying the individual printers 100. In other words, the ink specification information may be information capable of finally specifying the kind of ink required to be supplied to the individual printers.

(7) In the second embodiment, the output unit 250 is a liquid crystal panel provided in the ink supply apparatus 200 (see the center part of FIG. 1 and the left part of FIG. 4). However, it is also possible to provide the output unit in other forms, such as a tablet computer or a smart phone that is independent of the ink supply apparatus and is wirelessly connected to the ink supply apparatus.

(8) In the above-described first embodiment, the ink supply apparatus 200 includes the n ink storage units 211 to 21n and the n ink discharging units 221 to 22n. Further, the n ink discharging units 221 to 22n are respectively coupled to the n ink storage units 211 to 21n (also referred to as the ink storage units 21i) different from one another (see the top left part of FIG. 1). However, the ink supply apparatus may include one ink discharging unit which can be coupled to the plurality of ink storage units 211 to 21n and discharge the ink stored in any one of the plurality of ink storage units 211 to 21n to a printer by switching the coupling with the plurality of ink storage units 211 to 21n.

(9) In the above-described first embodiment, the ink supply apparatus 200 is installed in the general affairs department in the company. In the second embodiment, the ink supply apparatus 200b is configured such that the operator OP can carry the ink supply apparatus 200b on their back (see the left part of FIG. 1 and the left part of FIG. 4). However, the ink supply apparatus may be configured in other forms. For example, a plurality of sets of discharge coupling units 22/F and coupling tubes 22/T may be coupled to one ink storage unit 21i (i is an integer from 1 to n) included in the ink supply apparatus through piping in the building, and the respective discharge coupling units 22i/F may be disposed in a plurality of places in the building.

According to such an aspect, it is possible to reduce the distances by which the printers 100 are moved for refilling them with ink.

11

(10) In the above-described embodiments, the control unit 240 of the ink supply apparatus 200 can also discharge ink based on a supply instruction Is received from the management server 300 and ink specification information Ii read by the information reading unit 230 (see the center part and middle right part of FIG. 1). Therefore, (i) the ink supply apparatus 200 may be configured to collate the supply instruction Is received from the management server 300 with ink specification information Ii read by the information reading unit 230 to specify the ink to be discharged. Also, (ii) the supply system may be configured such that the ink specification information Ii held by the printers 100A to 100C does not include information for specifying the printers 100A to 100C. In the aspect (i), it is possible to reduce the risk of discharging inappropriate ink to the printers 100A to 100C. In the aspect (ii), it is possible to reduce the information amount of the ink specification information Ii.

(11) In the above-described embodiments, the operator of the ink supply apparatus 200 supplies ink to the ink storage units 11j of the printers 100 (see the left part of FIG. 1 and the left part of FIG. 4). However, the users of the printers 100 may supply ink to the ink storage units 11j of the printers 100, using the ink discharging units 22i, in response to the output of the output unit 250 of the ink supply apparatus 200.

(12) In the above-described embodiments, the aspect in which one ink supply apparatus 200 supplies ink to the printers 100A, 100B, and 100C installed in the different departments in the company has been described (see FIG. 1). However, a plurality of ink supply apparatuses may supply ink to a plurality of printers installed in different departments in a company. Also, a plurality of ink supply apparatuses may supply ink to a plurality of printers installed in a plurality of companies.

In such aspects, the management server 300 may hold, in a storage device, correspondence information in which printers are associated with the ink supply apparatuses required to supply ink to the printers. When the management server 300 receives an ink supply request Rs from a printer, the management server 300 transmits, with reference to the correspondence information, a supply instruction Is to an ink supply apparatus corresponding to the printer having transmitted the ink supply request Rs.

(13) In the above-described embodiments, the management server 300 is connected to the ink supply apparatus 200 and the printers 100A, 100B, and 100C that are used in the same company, so as to be capable of communicating with them (see the center part of FIG. 1). Further, the management server 300 holds, in the auxiliary storage device, the information on the kinds of ink which are used in the printers 100A, 100B, and 100C in association with the information specifying the corresponding printer 100A, 100B, or 100C.

However, the management server 300 may be connected to a plurality of ink supply apparatuses 200 which are used in different companies and a plurality of printers 100 which are used in those companies. In such an aspect, the management server 300 may hold, in the auxiliary storage device, information on the kinds of ink which are used in the printers 100 in association with information specifying the individual printers 100.

(14) The management server 300 may be connected to a computer of an ink manufacturer or a computer of an agency of an ink manufacturer so as to be capable of communicating with such computer. Further, when the amount of ink stored in an ink storage unit 21i of the ink supply apparatus 200 is smaller than a predetermined threshold, the ink supply apparatus 200 may transmit an ink delivery request to the management server 300. When the management server 300

12

receives the ink delivery request, the management server 300 transmits a delivery instruction including information indicating the ink supply apparatus 200 having transmitted the ink delivery request, to the computer of the ink manufacturer or the computer of the agency of the ink manufacturer. The delivery instruction is a signal indicating that it is required to deliver ink to the ink supply apparatus 200 having transmitted the ink delivery request.

Also, a plurality of thresholds for the amount of ink of the ink supply apparatus 200 may be set such that whenever the amount of ink reaches one of the thresholds, a signal for notifying that is transmitted to the management server 300. Also, whenever a predetermined period of time elapses, or whenever a predetermined process such as supply of ink to a printer 100 is performed, the ink supply apparatus 200 may transmit the residual amount of ink of each ink storage unit 21i to the management server 300 such that the management server 300 can manage the residual amount of ink of the ink supply apparatus 200.

When the computer of the ink manufacturer receives the ink delivery request, the ink manufacturer sends ink to the ink supply apparatus 200 having transmitted the ink delivery request. When the computer of the agency of the ink manufacturer receives the ink delivery request, the agency of the ink manufacturer sends ink to the ink supply apparatus 200 having transmitted the ink delivery request. Charging for ink may be performed whenever ink is sent, or the price for ink may be paid based on a subscription contract.

D2. Second of Other Embodiments

Each of the printers 100A to 100C transmits an ink supply request Rs to the management server 300 when the amount of ink stored in the corresponding printer 100A, 100B, or 100C is smaller than the predetermined threshold (see the center part of FIG. 1). When the management server 300 receives the ink supply request Rs, the management server 300 transmits, to the ink supply apparatus 200, a supply instruction Is including information indicating the printer 100 having transmitted the ink supply request Rs. However, the supply system may be the system without including such a management server. Even in such an aspect, it is possible to supply ink from the ink supply apparatus to the printers without using detachable ink cartridges.

D3. Third of Other Embodiments

In the above-described embodiments, each of the ink discharging units 221 to 22n of the ink supply apparatus 200 stops discharging ink when the corresponding one of the ink sensing units 221S to 22nS detects ink (see FIG. 3). However, the ink supply apparatus may be the apparatus without including any ink sensing unit, and each printer may transmit a signal to the ink supply apparatus to stop supply of ink from the ink supply apparatus, when the printer detects that the amount of ink stored in the ink storage unit 21i reaches a predetermined threshold.

D4. Fourth of Other Embodiments

In the above-described embodiments, a reception coupling unit 12j/R and a discharge coupling unit 22j/F for passing different kinds of ink are configured in such shapes that they cannot be coupled to each other (see FIG. 2). However, a reception coupling unit and a discharge coupling unit for passing different kinds of ink may be configured in such shapes that they can be coupled to each other. In such

an aspect, a reception coupling unit and a discharge coupling unit for passing the same kind of ink may have portions having the same color and a reception coupling unit and a discharge coupling unit for passing different kinds of ink may have portions having different colors.

Even in this configuration, a discharge coupling unit 22iF of the ink supply apparatus 200 and a reception coupling unit 12jR of a printer 100 having the same color can be coupled to supply an appropriate kind of ink from the ink supply apparatus 200 to the printer 100. Further, since the user's attention is called to the colors, it is possible to prevent inappropriate kinds of ink from being supplied from the ink supply apparatus 200 to the printers 100.

D5. Fifth of Other Embodiments

In the above-described second embodiment, the ink supply apparatus 200b includes the fixing tool 280 (see FIG. 4). The operator of the ink supply apparatus 200b lifts the ink supply apparatus 200b onto their back and moves to the installation location of a printer 100 requiring supply of ink (see the arrow At2 of FIG. 4). However, the ink supply apparatus may be installed on a movable base such that the ink supply apparatus can be moved to the installation locations of the printers 100A to 100C. Also, all of the ink supply apparatus and the printers may be configured to be movable.

D6. Sixth of Other Embodiments

In the above-described first embodiment, the bases 400A to 400C can be moved by applying an external force to rotate the wheels 410 (see the bottom part and right part of FIG. 1). However, the printers 100 may be installed on bases having no wheels when they are used to print, and be mounted on a platform truck having wheels to be moved for receiving supply of ink.

E. Other Configurations

The present disclosure is not limited to the above-described embodiments and can be implemented in a variety of configurations without departing from the scope of the present disclosure. For example, the present disclosure can also be implemented in the following configurations. The technical features of the above-described embodiments corresponding to the technical features of the following individual configurations may be replaced or combined appropriately, in order to solve some or all of the problems described above or in order to achieve some or all of the effects described above. In addition, when a technical feature is not described as one which is essential in this specification, it is able to remove the technical feature as appropriate.

(1) According to a configuration of the present disclosure, a supply system for supplying ink to a plurality of printers is provided. In the supply system, each of the plurality of printers holds an ink specification information for specifying a kind of ink to be supplied to the printer, and the supply system includes an ink supply apparatus. The ink supply apparatus includes a plurality of ink storage units storing different kinds of ink, a plurality of ink discharging units each of which is coupled to a corresponding one of the plurality of ink storage units and discharges, to the printer, the ink stored in the coupled ink storage unit, an information reading unit that reads the ink specification information held by the printer, and a control unit that controls an ink

discharging unit of the plurality of ink discharging units and causes the ink discharging unit to discharge ink, the ink discharging unit being coupled to the ink storage unit storing the kind of ink specified by the ink specification information read by the information reading unit.

In this aspect, an appropriate kind of ink can be supplied from the ink supply apparatus to the printers by using the ink specification information held by the printers. Further, an appropriate kind of ink can be supplied to the printers without detaching the components for storing ink in the printers from the printers. For this reason, all of the printers can be consistently used without discarding the components for storing ink in the printers or using them as objects of material recycling within shorter periods as compared to the bodies of the printers. Therefore, the burden on the environment is reduced.

(2) The supply system of the above-described configuration may further include a management server connected to and configured to communicate with the ink supply apparatus and the plurality of printers. Each of the plurality of printers may transmit a first signal to the management server when an amount of ink stored in the printer is smaller than a predetermined threshold, and when the management server receives the first signal, the management server may transmit, to the ink supply apparatus, a second signal including information indicating the printer that transmitted the first signal, and the ink supply apparatus may include an output unit to output information, and when the ink supply apparatus receives the second signal, the ink supply apparatus may cause the output unit to output information for urging supply of ink to the printer that transmitted the first signal.

According to this aspect, the operator of the ink supply apparatus supplies ink from the ink supply apparatus to the printer in response to the output of the output unit. Therefore, it is possible to refill the printer with ink when the amount of ink is smaller than a predetermined threshold, before the printer is caused to be unable to print by a shortage of ink. Further, it is possible to avoid refilling, with ink, a printer storing a sufficient amount of ink. In other words, it is possible to reduce the number of times of refilling a printer with ink.

(3) In the supply system of the above-described configuration, each of the ink discharging units may include an ink sensing unit that can detect ink and can be inserted into the printer when ink is discharged to the printer, and each of the ink discharging units may stop discharging ink when the ink sensing unit detects ink.

According to this aspect, it is possible to supply ink to a printer without spilling ink out of the printer.

(4) In the supply system of the above-described configuration, each of the plurality of printers may include reception coupling units each of which can be coupled to a corresponding one of the plurality of ink discharging units and receive ink, and each of the plurality of ink discharging units may include a discharge coupling unit that can be coupled to a corresponding one of the reception coupling units of the plurality of printers and discharge ink, and the reception coupling unit and the discharge coupling unit for passing different kinds of ink may be configured to have shapes unable to be coupled to each other, and the reception coupling unit and the discharge coupling unit for passing the same kind of ink may be configured to have shapes enabled to be coupled to each other.

According to this aspect, it is possible to supply appropriate kinds of ink from the ink supply apparatus to a printer by connecting the discharge coupling units of the ink supply apparatus to the reception coupling units of the printer.

15

(5) In the supply system of the above-described configuration, the ink supply apparatus may include a fixing tool for fixing the ink supply apparatus to a human body.

According to this aspect, it is possible for a person with the ink supply apparatus fixed on them to move to the installation location of a printer and supply ink from the ink supply apparatus to the printer.

(6) In the supply system of the above-described configuration, each of the plurality of printers may be installed on a movable base having wheels.

According to this aspect, each printer installed on a base can be moved to the installation location of the ink supply apparatus such that ink can be supplied from the ink supply apparatus to the printer.

The present disclosure can also be implemented in a variety of configurations other than the supply system. For example, the present disclosure can be implemented in configurations such as a supply system manufacturing method, a supply system operating method, a consumable supply method, computer programs for implementing those methods, and non-temporary recording media having those computer programs recorded thereon.

What is claimed is:

1. A supply system for supplying ink to a plurality of printers that use different ink sets, each of the plurality of printers having a barcode representing ink specification information of the printer that includes information on a model of the printer, information for individually identifying the printer, and information on one-to-one correspondence between each of the plurality of printers and a respective ink set used by the printer, the supply system comprising an ink supply apparatus, wherein

the ink supply apparatus includes

a plurality of ink storage units storing different kinds of ink,

a plurality of ink discharging units each of which is coupled to a corresponding one of the plurality of ink storage units and discharges, to the printer, the ink stored in the coupled ink storage unit,

an information reading unit that reads the barcode of the printer and obtains the model of a printer and the ink set that is in one-to-one correspondence with the printer from the ink specification information of the printer, and

a control unit that controls an ink discharging unit of the plurality of ink discharging units and causes the ink discharging unit to discharge ink, the ink discharging unit being coupled to the ink storage unit storing the

16

kind of ink specified by the ink specification information read by the information reading unit.

2. The supply system according to claim 1, further comprising:

a management server connected to and configured to communicate with the ink supply apparatus and the plurality of printers, wherein

each of the plurality of printers transmits a first signal to the management server when an amount of ink stored in the printer is smaller than a predetermined threshold, and

when the management server receives the first signal, the management server transmits, to the ink supply apparatus, a second signal including information indicating the printer that transmitted the first signal,

the ink supply apparatus includes an output unit to output information, and

when the ink supply apparatus receives the second signal, the ink supply apparatus causes the output unit to output information for urging supply of ink to the printer that transmitted the first signal.

3. The supply system according to claim 1, wherein

each of the ink discharging units includes an ink sensing unit configured to detect ink and be inserted into the printer when ink is discharged to the printer, and each of the ink discharging units stops discharging ink when the ink sensing unit detects ink.

4. The supply system according to claim 1, wherein

each of the plurality of printers includes reception coupling units each of which is to be coupled to a corresponding one of the plurality of ink discharging units and receives ink, and

each of the plurality of ink discharging units includes a discharge coupling unit which is to be coupled to a corresponding one of the reception coupling units of the plurality of printers and discharges ink,

the reception coupling unit and the discharge coupling unit for passing different kinds of ink are configured to have shapes unable to be coupled to each other, and the reception coupling unit and the discharge coupling unit for passing a same kind of ink are configured to have shapes enabled to be coupled to each other.

5. The supply system according to claim 1, wherein

the ink supply apparatus includes a fixing tool for fixing the ink supply apparatus to a human body.

6. The supply system according to claim 1, wherein

each of the plurality of printers is installed on a base that includes a wheel and that is configured to move.
